CRUSHING ROLLS

Philip M. McKenna, Greensburg, Pa., assignor to Kennametal Inc., Latrobe, Pa., a corporation of Pennsylvania
Filed May 29, 1961, Ser. No. 113,307
6 Claims. (Cl. 241—294)

This invention relates to the composition, structure, and arrangement of crushing rolls for use in conventional crushing equipment for the size reduction of various materials.

One conventional type of crushing equipment uses two cylindrical rolls, each comprising a solid cylindrical core of tough steel and a removable outer shell of hard steel that is intended to resist abrasion. Generally, one of the rolls is adjustable relative to the other and is supported on strong springs. The material to be crushed is fed in a stream between the rolls, the crushing capacity of which is proportional to their peripheral speed. Heretofore, it has not been practicable to operate crushing rolls at high speeds, because at higher speeds slippage occurs between the rolls and the feed, resulting in abrasive action that wears the rolls very rapidly. Even at lower speeds, there is appreciable wear, which is not uniformly distributed throughout the length of the rolls but tends to be concentrated at different points, with the result that grooves are worn in the rolls at those points, diminishing their efficiency and producing material that is less uniformly sized; and this grooving effect increases as the speed of the rolls increases.

It is among the objects of this invention to provide a crushing roll or rolls for use in conventional crushing equipment of various types that will overcome the foregoing difficulties and that can be operated at very high peripheral speeds without substantial abrasion or grooving of the roll surfaces.

Another object is to provide a crushing roll or rolls that may be operated at such high peripheral speeds that crushing efficiency is greatly increased by the inertia of the roll itself when rotating at such speeds.

A further object is to provide a composite crushing roll having an outer shell of very hard metal of high density supported by a thin-walled sleeve of resilient material on a central drive shaft, which can be revolved at a sufficiently high speed to enable the roll to resist the forces of crushing in a resilient manner by the inertia of the heavy outer shell and, because of the hardness of that shell, without substantial abrasion or grooving of the roll surface.

A still further object is to provide an improved composite crushing roll that fulfills the foregoing objectives and, in addition, can be used in a conventional crushing machine either with an opposed roll of the same type or an opposed roll of conventional design; in the latter case, the characteristics inherent in the improved composite roll being such that they will effectively prevent or substantially reduce the tendency of the opposed conventional roll to acquire a grooved surface when operating at conventional and higher speeds.

Other objects of the present invention will be apparent from the following description of a preferred embodiment in connection with the accompanying drawings, in which:

FIG. 1 is a front elevation, partly in section, of the composite roll of this invention;

FIG. 2 is a fragmentary front elevation, in section, of the roll shown in FIG. 1, with the wedge rings supporting the outer shell shown in their initial positions before final assembly of the roll;

FIG. 3 is an end elevation, on a reduced scale, of the roll shown in FIG. 1;

FIG. 4 is a diagrammatic end elevation of a conven-

2

tional roll crusher, in which are mounted two opposed composite rolls made in accordance with the present invention;

FIG. 5 is a diagrammatic end view of two opposed rolls adapted for use in the crusher of FIG. 4, one of said rolls being of the composite type of this invention and the other being a conventional roll; and

FIG. 6 is a modification of FIG. 5, in which the conventional roll is of larger diameter than the composite roll, the rolls being adapted for use in a conventional crusher of larger size than that shown in FIG. 4.

The crushing roll of this invention comprises an outer shell of hard metallic composition, preferably cemented tungsten carbide or the like, having a specific gravity greater than 10 and a Young's modulus of elasticity at least twice that of steel. The shell has a cylindrical outer surface and opposed double frusto-conical inner surfaces. The shell is supported on a central shaft by a pair of wedge rings, the inner surfaces of which are cylindrical and fit the shaft snugly and the outer surfaces of which are tapered to conform to the taper of the inner surfaces of the shell. Between the inner surfaces of the shell and the outer surfaces of the wedge rings is a thin layer or sleeve of resilient material that is preferably under radial compression in the assembled roll. This composite roll is adapted to be used in conventional roll crushers of various types either opposed to a similar roll or opposed to a conventional roll. In the latter case, it may be advantageous in some cases to have the conventional roll of larger diameter and to rotate it at a lower speed than the other roll.

Referring to the drawings, the improved composite roll A of this invention includes a cylindrical shaft 1, preferably of tough steel, with a central portion 2 terminating in shoulders 3. Mounted on the central portion of this shaft are two wedge rings 4 and 5, also desirably of tough steel. The combined axial length of these rings is somewhat less than the length of the central portion of the shaft. The rings are machined to a snug fit on the shaft, and their outer circumferential surfaces 6 are tapered uniformly so that the adjacent inner ends 7 of the rings are of smaller diameter than the outer ends 8.

Roll A also includes an outer shell 11, preferably of cemented tungsten carbide or similar material having a specific gravity that is greater than 10 and a Young's modulus of elasticity that is more than twice that of steel. The shell has a cylindrical outer surface 12 and opposed, uniformly tapered inner surfaces 13 and 14, such that the inside diameter of the shell at the center is less than its inside diameter at the ends. To avoid strains, a portion of the central inner surface 15 of the shell is preferably cylindrical, so that the shell has opposed, double frusto-conical inner surfaces that have the same angle of taper, preferably about 10°, as the outer circumferential surfaces of the wedge rings; and these inner surfaces are separated by a short cylindrical surface. The shell is desirably as long as the central portion 2 of the shaft 1. The tapered inner surfaces of the shell are slightly larger in diameter than the corresponding portions of the wedge rings when the ends of those rings are flush with the ends of the shell. The resulting annular space between the wedge rings and the shell is filled with resilient material 16, such as rubber, that is preferably under radial compression in the final roll assembly.

In assembling the composite roll, the shell is placed over the central portion of the shaft and supported more or less concentrically therewith. The wedge rings, with a sleeve of resilient rubber bonded on the outer surface of each ring, are then placed over the shaft from each end and their inner ends are pushed together towards the center of the shell. FIG. 2 shows the approximate posi-

tion of the wedge rings when they have been pushed in place far enough that the rubber layer 16, without being compressed, fills the tapered annular space between the rings and the shell. For drawing the rings further into the shell and thereby subjecting the resilient material to radial compression, the rings may conveniently be provided with a plurality of longitudinal holes 17, parallel to the axis of the roll. Through these holes, when they are aligned, may be passed rods 18 with threaded ends. By tightening nuts 19 on the ends of these rods, the wedge rings may be drawn axially inward towards the center of the roll until the rubber sleeves have been subjected to the desired degree of compression, which will generally occur when their thickness has been reduced by about 50 percent, depending on the characteristics of the resilient material used. For example, with a 12-inch long roll having an overall diameter of 12 inches and having the wedge rings tapered at an angle of 10°, it has been found satisfactory to use a rubber sleeve having a thickness of about $\frac{3}{32}$ of an inch before it is compressed. After the wedge rings have been pressed into the shell, the outer ends of the rings will be flush, or can be machined flush, with the ends of the shell and the shoulders 3 on the shaft. If desired, the rings may then be secured to the shaft by welding as at 21 (see FIG. 1) and the rods 18 removed.

The resilient rubber sleeve 16 between the wedge rings and the shell compensates for the greater coefficient of thermal expansion of the steel wedge rings, which is two and one-half to three times that of the tungsten carbide shell. Without such a resilient layer, the shell would tend to rupture as the roll became heated in use. The resilient layer also permits the roll to resist the shocks and forces of crushing in a resilient manner not only by its own cushioning effect, but also (due to its substantial confinement between the shell and the wedge rings) by acting in the manner of a hydraulic fluid to distribute the localized shocks of crushing to other portions of the roll.

It is a feature of the composite roll of this invention that it can be rotated at very high surface speed during the crushing operation. Because of the hard surface of the tungsten carbide outer shell, such speeds do not cause appreciable wear or grooving of the roll surface, as they do with conventional steel rolls alone.

A great advantage of such higher speed is that the capacity of a set of rolls is increased several times that attainable by steel rolls of equal size rotated at lower peripheral speeds. In other words, using the composite rolls of this invention, a crushing machine of a given size can do the work of a much heavier and larger machine using conventional rolls. This advantage is of considerable importance wherever the transport of crushing machines to remote sites is involved, as, for example, at distant mines for crushing ore or at remote airfields for crushing ballast to dress the field.

The composite roll of this invention may be used in various combinations and arrangements in conventional roll crushing equipment. For example, as shown in FIG. 4, two of these rolls A and A' may be used in a conventional two-roll crusher 30. Roll A is mounted on fixed bearings. Roll A' is resiliently mounted in a conventional manner on a bearing bracket 31, one end of which is pivotally mounted at 32 to the base of the crusher and the other end of which is resiliently supported by springs 33. This arrangement permits throat 34 between the rolls to open up against the urging of springs 33 when an unusually hard lump of material to be crushed enters the slot between the rolls. It has been found that the composite rolls of this invention possess inherent protective features in addition to the cushioning and distributive effects of the resilient layer that have been mentioned above. Since the carbide shell has a density nearly twice that of steel and since it is mounted on the outer periphery of the roll and is rotated at a very high speed (that would be destructive of opposed steel rolls), it possesses exceptionally high rotational inertia compared to a conventional steel roll. When an unusually hard or tough

lump of feed material enters the slot between two such composite rolls, and not in the exact center of that slot, the forces generated tend not only to open the slot but also to open one end more than the other. Such twisting forces on the shell are resisted in a resilient manner by its rotational inertia, which is large enough to have a pronounced gyroscopic and centering effect. This gyroscopic reaction of the shell is much more prompt than the reaction of the supporting springs 33, so that the initial shock of impact has less chance of damaging the rolls than when the protective action of the springs alone is relied upon. In addition, the high density of the composite roll of this invention (as compared to conventional crushing rolls of the same size) is equivalent to a large inertia that yieldably resists displacement of the rolls in any direction.

5 10 15 20 25 30 35 40 45 50 55 60 65 70 75

A further advantage of the roll arrangement in FIG. 4 is that, with two opposed carbide surfaced rolls, their wear is so negligible that they can be used to crush various materials without serious contamination by worn-off particles of the rolls, thus permitting the economies of roll crushing not heretofore even possible because of the excessive wear of conventional crushing rolls even at low speeds.

In addition, it has been found that when the composite roll of this invention is used with an opposed steel roll of conventional design, the performance of the latter is unexpectedly improved. Where, as in FIG. 5, both rolls are of the same diameter and are rotated at the same speed (a speed well above that which would cause grooving of two opposed steel rolls), the composite carbide roll A unexpectedly performs a truing function that entirely prevents or greatly reduces grooving of the opposed steel roll B. A possible explanation of this phenomenon may reside in the fact that, at the high speeds at which the rolls rotate, there is considerable slippage between the material that is fed between the rolls and the rolls themselves. The resulting abrasive action, which inevitably causes grooving where two opposed steel rolls are used, results in a dressing or truing action when one of the rolls is a composite carbide roll of this invention and the other a steel roll. Because the carbide roll itself is not substantially affected by the abrasive action of the feed and does not itself become grooved, the feed is more or less evenly distributed between the rolls and tends to avoid grooving the steel roll; or, if such grooves are started, they tend to be eliminated by the dressing or truing action referred to. The advantage of this type of arrangement, in which the composite carbide roll is opposed by a conventional steel roll, is that many of the benefits pointed out above of two carbide rolls are obtained at the cost of a single such roll.

In addition, the carbide roll of this invention can be used, as shown in FIG. 6, with a conventional steel roll of larger diameter. In this arrangement, the carbide roll A is maintained at a sufficiently high speed to obtain the inertial advantages previously referred to, while the steel roll C (about $2\frac{1}{2}$ times the diameter of A) is preferably rotated at a lower peripheral speed. The surface speed differential between the rolls produces a shearing stress on the material being crushed, which in many cases is advantageous to and facilitates the crushing operation. In other words, the material fed between the rolls is subjected not only to a crushing force as in conventional rolls but also to a differential shearing action that helps to disintegrate the material. Apparently, the feed material in the throat of the rolls is subjected to a high concentration of crushing forces by the smaller, incisive composite roll A, while at the same time the feed is held back, in effect, by friction with the slower moving steel roll. As a result, lumps of feed material are broken with less expenditure of force than if both rolls were of large size.

According to the provisions of the patent statutes, I have explained the principle of my invention and have illustrated and described what I now consider to represent its best embodiment. However, I desire to have it

understood that, within the scope of the appended claims, the invention may be practiced otherwise than as specifically illustrated and described.

I claim:

1. A crushing roll comprising an outer shell of hard metallic composition having a specific gravity greater than ten and having a Young's modulus of elasticity at least twice that of steel and having a substantially lower coefficient of thermal expansion than steel, the shell having opposed double frustro-conical inner surfaces tapering radially inwards towards the center of the shell, a shaft concentric with the shell, a pair of steel wedge rings mounted on the shaft, each ring having a frustro-conical outer circumferential surface conforming to an inner surface of the shell, and a layer of resilient material between the tapered surfaces of the rings and shell to yieldably compensate for the difference in the coefficients of thermal expansion of the steel wedge rings and the shell.

2. A crushing roll according to claim 1, in which the outer shell is made of cemented tungsten carbide.

3. A crushing roll according to claim 1, in which the resilient material is radially compressed between the tapered surfaces of the rings and shell.

4. A composite crushing roll comprising a cylindrical shaft, a pair of steel wedge rings mounted on the shaft with their inner ends spaced from each other, the outer circumferential surfaces of the rings being tapered inwardly from their outer ends towards their inner ends, a thin walled sleeve of resilient material mounted on the tapered circumferential surface of each ring, and an outer shell of cemented tungsten carbide having two tapered inner

surfaces each conforming in their angle of taper to the tapered surface of a different wedge ring, the resilient sleeves being under radial compression between the tapered surfaces of the rings and shell to yieldably compensate for the difference in the coefficients of thermal expansion of the steel wedge rings and the tungsten carbide shell.

5. A crushing roll according to claim 4, in which the sleeve is rubber and is compressed to about one-half of its original thickness.

10 6. A crushing roll according to claim 4, in which the angle of taper of the wedge rings is approximately ten degrees.
